β -SUBSTITUTED AMINOALKYL 2,6-DIALKYL SUBSTITUTED BENZOATES AND METHOD OF MAKING THE SAME

Norman Rabjohn, Columbia, Mo., assignor to Curators of the University of Missouri, Columbia, Mo., a public corporation of Missouri

No Drawing. Application May 27, 1954
Serial No. 432,918

12 Claims. (Cl. 260—477)

The present invention relates to novel chemical compounds; and, more particularly, the invention relates to β -substituted aminoalkyl dialkylsubstituted benzoates and salts thereof possessing valuable pharmacological properties.

β -Diethylaminoethyl p-aminobenzoate (procaine) and its salts, such as the hydrochloride, and β -dimethylaminoethyl p-butylaminobenzoate hydrochloride (tetracaine hydrochloride) are well known local anesthetics. The physiological effect of such compounds is limited in duration, decreasing relatively rapidly as time elapses after injection.

It is the principal object of the present invention to provide novel chemical compounds possessing valuable pharmacological properties.

It is another object of the invention to provide novel chemical compounds possessing local anesthetic properties.

A further object of the invention is to provide novel chemical compounds possessing local anesthetic properties comparable to those of procaine and tetracaine which, however, upon injection, provide a local anesthetizing effect of substantially longer duration than do the prior compounds.

Other objects will become apparent from a consideration of the following specification and claims.

The novel compounds of the present invention are β -substituted aminoalkyl 2,6-dialkylsubstituted benzoates possessing the fundamental structure:

wherein R₁ and R₂ are alkyl groups containing from 1 to 3 carbon atoms; where R₃, R₄, and R₅ are selected from the group consisting of hydrogen and alkyl groups containing from 1 to 3 carbon atoms; wherein R₆ is a saturated aliphatic chain containing from 2 to 4 atoms; and wherein R₇ and R₈ are selected from the group consisting of alkyl groups containing from 1 to 4 carbon atoms, the total carbon atoms in R₇ plus R₈ not exceeding 6, and a pentamethylene linkage,

It will be noted from the foregoing that the compounds within the general formula are related to procaine and tetracaine. Nevertheless, although the compounds of the invention possess local anesthetic properties on the order of procaine and tetracaine, they possess a further property not possessed by either of these local anesthetics, namely

2

extended duration of anesthetizing effect upon injection. The exact reason for this is not fully understood. However, in the light of tests with procaine, on the one hand, and the compounds of the invention, on the other hand, it would appear that the relatively rapid loss of effect after injection of the procaine or tetracaine is due to hydrolysis of the ester group in the presence of enzymes. The compounds of the present invention possess, however, marked resistance to hydrolysis, and this is believed to be due to a steric hindering effect provided by the alkyl substituents ortho to the ester group. At any rate it has been found that compounds of the invention have, in addition to a much lower rate of hydrolysis, a substantially longer anesthetizing effect as compared to compounds related but for the ortho substituents. For example, equianesthetic solutions of the compounds produce, in comparison with the common clinically-employed procaine and tetracaine, several times longer duration of topical and intracutaneous anesthesia in man and animals.

20 This duration is even greater when the compounds are employed in ointment form.

As stated, in the compounds of the invention each of the positions on the benzene ring ortho to the ester group is provided with an alkyl substituent. These alkyl groups, R₁ and R₂ in the above formula, may contain from 1 to 3 carbon atoms, such as methyl, ethyl or propyl. In any one compound R₁ and R₂ may be the same or may be different, although from the standpoint of ease of manufacture it is preferred that R₁ and R₂ be the same groups.

25 The remaining substituents on the benzene ring, namely R₃, R₄ and R₅ may be hydrogen or one or more thereof may be a simple alkyl group of the type mentioned above with respect to R₁ and R₂.

30 The ester group of the compounds is a β -disubstituted 35 aminalkyl group,

40 R₆ is a saturated aliphatic chain containing from 2 to 4 carbon atoms, and since the ester group, as stated, is a β -substituted aminoalkyl group, R₆ will be an ethylene or alkyl-substituted ethylene chain. Thus, R₆ may be ethylene itself, 1 - methylethylene, 2 - methylethylene, 1,2 - di-

45 methylethylene, 1,1 - dimethylethylene or 2,2 - dimethyl-ethylene. R₇ and R₈ may be alkyl groups containing from 1 to 4 carbon atoms such as methyl, ethyl, propyl or butyl groups. It is advisable, however, that the total

50 number of carbon atoms in R₇ plus R₈ not exceed six. Hence, where R₇, for example, is a butyl group, R₈ will be a methyl or ethyl group, and so on. R₇ and R₈ may also join to provide a pentamethylene chain attached to the nitrogen atom to provide the group

55 The preferred compounds from the standpoint of optimum local anesthetic action and duration of effect are 60 those possessing the fundamental structure:

65 where R₁ and R₂ are alkyl groups containing from 1 to 3 carbon atoms; and where R₃, R₄ and R₅ are selected from

the group consisting of hydrogen and alkyl groups containing from 1 to 3 carbon atoms.

In the compounds of the invention there is a basic nitrogen in the ester group to which an equivalent of acid may be added to form a salt. Hence, the compounds of the invention may be prepared and/or employed either as the base or as a salt. Thus, for example, the structural formula for the hydrochloride of the compounds of the present invention may be written as follows:

In view of the fact that the salts differ from the bases only in the addition of acid to the nitrogen atom referred to, and are characterized by the same fundamental structural formula, the salts as well as the bases are included within the scope of this application and of the claims wherever reference is made to compounds having a stated fundamental structure.

The acid forming the salt may be any inorganic or organic acid desired, for example, hydrochloric, hydrobromic, hydriodic, nitric, sulfuric, phosphoric, and the like; acetic, propionic, caproic, stearic, and other acids of this series, and the like; crotonic, oleic, oxalic, citric, tartaric, lactic, benzoic, naphthoic, picric, salicylic, dilituric, methane sulfonic, camphor sulfonic, and the like. When a salt is to be administered, any toxicity or other undesirable effect which may be imparted by the acid will be taken into consideration as well known in the art.

The compounds may be readily prepared by reacting one mole of the appropriate 2,6-dialkyl substituted benzoic acid,

where the various R groups are as discussed above, with one mole of the appropriate β -disubstituted aminoalkyl chloride hydrochloride in the presence of two equivalents of a weakly alkaline material insoluble in the reaction mixture, such as potassium bicarbonate or sodium bicarbonate, which neutralizes the hydrogen chloride of the reactant and produced during the reaction. The reaction is preferably carried out under anhydrous conditions using, for example, dry toluene as solvent. Elevated temperatures speed the reaction, and refluxing is recommended. The product can be separated from the reaction medium by any one of a wide variety of means. The material thus obtained can be worked up following conventional techniques for purification.

The base may be readily converted to the desired salt by treatment with the appropriate acid. For example, in converting the base to the hydrochloride, it may be treated, while in solution, for example, in toluene, with anhydrous gaseous hydrogen chloride.

The 2,6-dialkyl substituted benzoic acids referred to above may be readily prepared by any one of a variety of procedures known in the art and recorded in the

literature. For instance the appropriate 2,6-dialkyl substituted benzene,

where the various R groups are as described above, may be brominated to attach a bromine atom to the ring carbon atom between R₁ and R₂. The resulting bromobenzene may then be converted to the corresponding carboxylic acid in accordance with the Grignard reaction.

The compounds of the invention and their preparation will be more readily understood by a consideration of the following specific examples which are given for the purpose of illustration only and are not to be construed as limiting the scope of the invention in any way.

EXAMPLE I

20 2,6-dimethylbenzenediazonium chloride, prepared in the usual manner from 50 g. 2,6-dimethylaniline, is added to a cold suspension of mercuric bromide formed by treating 71 g. of mercuric nitrate with 103 g. of sodium bromide in 300 ml. of water. The complex is collected 25 by filtration and dried. It is then mixed with 350 g. of finely ground sodium bromide, and the mixture added slowly to a flask heated to 90° C. in an oil bath. After decomposition is complete, the reaction mixture is extracted repeatedly with benzene. The combined benzene extracts 30 are washed with dilute hydrochloric acid, dilute sodium hydroxide solution and water. The benzene is removed by distillation on a steam bath, and the residue is distilled under vacuum to give 2,6-dimethylbromobenzene, 35 boiling at 101–103° C./22 mm.

A Grignard reagent is prepared in the usual manner from 18.5 g. of the 2,6-dimethylbromobenzene, 2.6 g. of magnesium, a small amount of ethyl bromide and 150 ml. anhydrous ether. The Grignard solution is poured onto Dry Ice, and, after the latter has evaporated, 40 the reaction mixture is acidified with dilute hydrochloric acid. The ether layer is separated and worked up to yield 2,6-dimethylbenzoic acid melting at 113–115° C.

A mixture of 6 g. (0.04 mole) of 2,6-dimethylbenzoic acid, 8.3 g. (0.083 mole) of potassium bicarbonate, 8.3 g. (0.048 mole) of β -diethylaminoethyl chloride hydrochloride and 160 ml. of toluene is refluxed under a Stark and Dean trap, to remove water, for 30 hours. The reaction mixture, after being allowed to cool, is washed with dilute sodium hydroxide solution and water and then dried over anhydrous magnesium sulfate. The dry toluene solution is treated with anhydrous hydrogen chloride to precipitate β -diethylaminoethyl 2,6-dimethylbenzoate hydrochloride which melts at 161–164° C. after recrystallization from a mixture of absolute ether and 55 absolute alcohol.

The calculated C and H analysis for $C_{15}H_{24}O_2NCl$ is: C, 63.0; H, 8.4; that found is: C, 62.9; H, 8.3.

A 1% solution of this compound administered intracutaneously anesthetizes the skin of a guinea pig for 60 45–60 minutes.

EXAMPLE II

Mesitylene is brominated according to the procedure of L. I. Smith, Organic Synthesis, Coll. Vol. II, p. 95, 65 to give bromomesitylene boiling at 110–112° C./18 mm.

This bromomesitylene is then converted to mesitoic acid (2,4,6-trimethylbenzoic acid) by the method of R. P. Barnes, Organic Synthesis, 21, p. 77 (1941), using 95 g. of bromomesitylene, 12.1 g. of magnesium, 380 ml. of dry ether and an excess of Dry Ice.

A mixture of 8.2 g. (0.05 mole) of 2,4,6-trimethylbenzoic acid, 10.4 g. (0.06 mole) of β -diethylaminoethyl chloride hydrochloride, 11.0 g. (0.11 mole) of potassium bicarbonate and 200 ml. of toluene is refluxed under 70 a Stark and Dean trap for 22 hours. The reaction mix-

ture, after being permitted to cool, is washed twice with 10% sodium hydroxide solutions and once with water, and then dried over anhydrous magnesium sulfate. The dry toluene solution is treated with anhydrous hydrogen chloride and the precipitate collected. Recrystallization of the precipitate from a mixture of absolute alcohol and absolute ether, results in β -diethylaminoethyl 2,4,6-trimethylbenzoate hydrochloride melting at 182-183.5° C.

The calculated C and H analysis for $C_{18}H_{26}O_2NCl$ is: C, 64.1; H, 8.7; that found is: C, 64.1; H, 9.0.

A 1% solution of this compound injected intracutaneously anesthetizes the skin of a guinea pig for 55-70 minutes.

Following the foregoing procedure but using β -dimethylaminoethyl chloride hydrochloride or β -diisopropylaminoethyl chloride hydrochloride in place of the β -diethylaminoethyl chloride hydrochloride the corresponding β -dimethylaminoethyl 2,4,6-trimethylbenzoate hydrochloride and β -diisopropylaminoethyl 2,4,6-trimethylbenzoate hydrochloride may be prepared.

EXAMPLE III

Following the procedure of Newman and Lloyd, J. Am. Chem. Soc. 74, p. 2672 (1952), bromodurene (boiling at 120-123° C./15 mm.) is prepared from 26 g. of durene and 33.4 g. of bromine.

Following the procedure also set forth in the above-cited article, 24 g. of the bromodurene is converted to 2,3,5,6-tetramethylbenzoic acid (melting at 175.5-179° C.) using 15.7 g. of ethyl bromide, 7.8 g. of magnesium and an excess of Dry Ice.

A mixture of 4 g. (0.0225 moles) of 2,3,5,6-tetramethylbenzoic acid, 4.3 g. (0.025 mole) of β -diethylaminoethyl chloride hydrochloride, 4.5 g. (0.045 mole) of potassium bicarbonate and 100 ml. of toluene is refluxed under a Stark and Dean trap for 22 hours. The reaction mixture, after cooling, is washed twice with 10% sodium hydroxide solution and once with water, and then dried over anhydrous magnesium sulfate. Anhydrous hydrogen chloride is then passed into the dry toluene solution and the precipitate is collected. After recrystallization from a mixture of absolute alcohol and absolute ether, the resulting β -diethylaminoethyl 2,3,5,6-tetramethylbenzoate hydrochloride melts at 192-194° C.

The calculated C and H analysis for $C_{18}H_{28}O_2NCl$ is: C, 65.0; H, 9.0; that found is: C, 64.8; H, 9.1.

A 0.75% solution of this compound injected intracutaneously anesthetizes the skin of a guinea pig for 80-90 minutes. When applied to unbroken human skin as an ointment, the duration of anesthesia is about six times as long.

EXAMPLE IV

From 25 g. of pentamethylbenzene and 26.7 g. of bromine, bromopentamethylbenzene, melting at 157-159.5° C., is prepared following the procedure of Clement, Ann. Chim., 13, p. 243 (1940).

Following the procedure also set forth in the article cited in the foregoing paragraph, the bromopentamethylbenzene is converted to 2,3,4,5,6-pentamethylbenzoic acid (melting at 204-207° C.), using 29 g. of bromopentamethylbenzene, 14.3 g. of ethyl bromide, 7.3 g. of magnesium and excess Dry Ice.

A mixture of 8.3 g. (0.043 mole) of the 2,3,4,5,6-pentamethylbenzoic acid, 7.5 g. (0.044 mole) of β -diethylaminoethyl chloride hydrochloride, 9.6 g. (0.096 mole) of potassium bicarbonate and 175 ml. of toluene is refluxed under a Stark and Dean trap for 30 hours. The reaction mixture, after being allowed to cool, is washed twice with 10% sodium hydroxide solution and once with water, and then dried over anhydrous magnesium sulfate. The dried toluene solution is treated with anhydrous hydrogen chloride and the resulting precipitate is collected. After recrystallization from a mixture of absolute alcohol and absolute ether, the resulting β -diethylaminoethyl

2,3,4,5,6 - pentamethylbenzoate hydrochloride melts at 204.5-206.5° C.

The calculated C and H analysis for $C_{18}H_{30}O_2NCl$ is: C, 65.8; H, 9.2; that found is: C, 66.0; H, 9.4.

5 A 1% solution of this compound injected intracutaneously anesthetizes the skin of a guinea pig for 80-90 minutes.

In place of the β -diethylaminoethyl chloride hydrochloride in the foregoing procedure there may be employed

10 β - diethylaminopropyl chloride hydrochloride, β - diethylaminoisopropyl chloride hydrochloride, β -diethylaminoethyl chloride hydrochloride, β -diethylaminosecondarybutyl chloride hydrochloride or β -diethylaminoisobutyl

15 chloride hydrochloride to prepare the corresponding β -diethylaminopropyl 2,3,4,5,6 - pentamethylbenzoate hydrochloride, β - diethylaminoisopropyl 2,3,4,5,6 - pentamethylbenzoate hydrochloride, β - diethylaminobutyl 2,3,4,5,6 - pentamethylbenzoate hydrochloride, β - diethylaminosecondarybutyl 2,3,4,5,6 - pentamethylbenzoate

20 hydrochloride and β -diethylaminoisobutyl 2,3,4,5,6-pentamethylbenzoate hydrochloride.

EXAMPLE V

25 Following the procedure of Fuson and Corse, J. Am. Chem. Soc., 60, p. 2065 (1938), there is prepared 2,4,6-triethylbromobenzene, boiling at 92-94° C./4 mm., from 324 g. of 1,3,5-triethylbenzene, 10 g. of powdered iron and 320 g. of bromine.

30 Following the procedure also set forth in the article cited in the foregoing paragraph, 2,4,6-triethylbromobenzene (120.5 g.) is converted to 2,4,6-triethylbenzoic acid (melting at 113-114° C.), using 12.5 g. of magnesium and an excess of Dry Ice.

35 A mixture of 20.6 g. (0.1 mole) of 2,4,6-triethylbenzoic acid, 20 g. (0.2 mole) of potassium bicarbonate and 250 ml. of toluene is refluxed under a Stark and Dean trap for 17 hours. Then 17.2 g. (0.1 mole) of β -diethylaminoethyl chloride hydrochloride are added, and the mixture is heated for an additional 111 hours. The reaction mixture is cooled and shaken once with a 100-ml. portion and twice with 50-ml. portions of 10% sodium hydroxide solution. The toluene layer is separated, washed once with water and dried over anhydrous magnesium sulfate.

40 Anhydrous hydrogen chloride is then bubbled through the toluene solution and the precipitate gathered and recrystallized from a mixture of absolute alcohol and absolute ether. The resulting β -diethylaminoethyl 2,4,6-triethylbenzoate hydrochloride melts at 145.5-146.5° C.

45 The calculated C and H analysis for $C_{19}H_{32}O_2NCl$ is: C, 66.7; H, 9.4; that found is: C, 66.4; H, 9.6.

50 A 1% solution of this compound injected intracutaneously anesthetizes the skin of a guinea pig for 45-60 minutes.

55 To prepare the corresponding β -(butylethylamino)ethyl 2,4,6-triethylbenzoate hydrochloride, β -(butylethylamino)ethyl chloride hydrochloride may be employed in the foregoing procedure in place of the β -diethylaminoethyl chloride hydrochloride.

EXAMPLE VI

60 Following essentially the method of Fuson and Corse, J. Am. Chem. Soc., 60, p. 2065 (1938), 2,3,5,6-tetraethylbromobenzene is prepared from 79 g. of tetrachethylbenzene, 66 g. of bromine and 10 g. of iron powder. The product boils at 97-99° C./0.5-1 mm.

65 Following a modification of the procedure also set forth in the above-cited article, 72 g. of the 2,3,5,6-tetraethylbromobenzene is converted to 2,3,5,6-tetraethylbenzoic acid (melting at 106-107.5° C.) using 54.5 g. of ethyl bromide, 18.9 g. of magnesium and excess Dry Ice. The modification consists of entraining the 2,3,5,6-tetraethylbromobenzene with ethyl bromide.

A mixture of 35.1 g. (0.15 mole) of the 2,3,5,6-tetraethylbenzoic acid, 30 g. (0.30 mole) of potassium bicarbonate and 250 ml. of toluene is heated under a Stark and Dean trap for about 20 hours. Then 25.8 g. (0.15 mole) of β -diethylaminoethyl chloride hydrochloride and 15 g. (0.15 mole) of potassium bicarbonate are added and heating is continued for an additional 114 hours. The reaction mixture is cooled and washed twice with 10% sodium bicarbonate solution and water. The toluene solution is dried over anhydrous magnesium sulfate and treated with dry hydrogen chloride. After crystallization from a mixture of absolute alcohol and absolute ether, the resulting β -diethylaminoethyl 2,3,5,6-tetraethylbenzoate hydrochloride melts at 151-152° C.

The calculated C and H analysis for $C_{21}H_{36}O_2NCl$ is: C, 68.2; H, 9.8; that found is: C, 67.8; H, 9.9.

Following the foregoing procedure, but employing β -piperidinoethyl chloride hydrochloride in place of the β -diethylaminoethyl chloride hydrochloride, the corresponding β -piperidinoethyl 2,3,5,6-tetraethylbenzoate hydrochloride may be prepared.

EXAMPLE VII

Following the procedure of Fuson and Horning, J. Am. Chem. Soc., 62, p. 2962 (1940), there is prepared from 408 g. of 1,3,5-triisopropylbenzene, 320 g. of bromine and 10 g. of iron powder, 478 g. of 2,4,6-triisopropylbromobenzene boiling at 145-148° C./18 mm.

Following the procedure also set forth in the above-cited article, with the exception that the 2,4,6-triisopropylbromobenzene is entrained with ethyl bromide, 141.5 g. of the former compound are converted to 2,4,6-triisopropylbenzoic acid (melting at 182-184° C.) using 5 ml. of ethyl bromide, 12.5 g. of magnesium and excess Dry Ice.

A mixture of 10.4 g. (0.04 mole) of the 2,4,6-triisopropylbenzoic acid, 8.3 g. (0.08 mole) of potassium bicarbonate and 250 ml. of toluene is refluxed for 8 hours under a Stark and Dean trap. Then 6.84 g. (0.04 mole) of β -diethylaminoethyl chloride hydrochloride are added and refluxing is continued for an additional 22 hours. The reaction mixture is shaken twice with 10% sodium hydroxide solution and once with water. The toluene solution is dried over anhydrous magnesium sulfate and treated with dry hydrogen chloride. Following recrystallization of the resulting precipitate from a mixture of absolute alcohol and absolute ether, the β -diethylaminoethyl 2,4,6-triisopropylbenzoate hydrochloride melts at 195.5-197° C.

The calculated C and H analysis for $C_{22}H_{38}O_2NCl$ is: C, 68.8; H, 10.0; that found is: C, 69.0; H, 10.2.

EXAMPLE VIII

The β -diethylaminoethyl 2,3,5,6-tetramethyl benzoate of Example III is dissolved in isopropyl alcohol and the solution treated with an equimolar amount of fumaric acid. The solid which precipitates upon the addition of ether is recrystallized from ethyl acetate to give β -diethylaminoethyl 2,3,5,6-tetramethyl benzoate fumarate melting at 110-120° C.

The calculated nitrogen analysis for $C_{21}H_{31}NO_6$ is: N, 3.6; that found is: N, 3.6.

The half lives, under hydrolysis conditions, of certain of the compounds of the foregoing examples were determined and compared with those of related compounds. The procedure employed is the modification of that of Tommila et al. as described by Price and Lincoln, J. Am. Chem. Soc., 73, p. 5836 (1951). This procedure measures the length of time required to hydrolyze half of the material tested under standard conditions.

The results are tabulated as follows:

Table

5	Compound	Time of one-half hydrolysis (hours)
10	1. β -diethylaminoethyl benzoate hydrochloride	0.25
	2. β -diethylaminoethyl 2-methylbenzoate hydrochloride	1.98
	3. β -diethylaminoethyl 3-methylbenzoate hydrochloride	0.40
	4. β -diethylaminoethyl 4-methylbenzoate hydrochloride	0.57
	5. β -diethylaminoethyl 4-amino benzoate hydrochloride (procaine)	7.1
15	6. β -diethylaminoethyl 2-methyl-4-aminobenzoate hydrochloride	40
	7. β -diethylaminoethyl 2,6-dimethyl benzoate hydrochloride	510
	8. β -diethylaminoethyl 2,4,6-trimethylbenzoate hydrochloride	450
	9. β -diethylaminoethyl 2,3,5,6-tetramethylbenzoate hydrochloride	350

20 Considerable modification is possible in the selection of the various substituents and salt forms without departing from the scope of the present invention.

I claim:

25 1. β -Substituted aminoalkyl 2,6-substituted benzoate compounds having the fundamental structure:

30 35 where R_1 and R_2 are alkyl groups containing from 1 to 3 carbon atoms; where R_3 , R_4 and R_5 are selected from the group consisting of hydrogen and alkyl groups containing from 1 to 3 carbon atoms; where R_6 is a saturated aliphatic chain containing from 2 to 4 carbon atoms, and

40 where R_7 and R_8 are selected from the group consisting of alkyl groups containing from 1 to 4 carbon atoms, the total number of carbon atoms in R_7 plus R_8 not exceeding 6, and a pentamethylene linkage,

45 2. β -Diethylaminoethyl 2,6-dialkyl substituted benzoate compounds having the fundamental structure:

55 60 where R_1 and R_2 are alkyl groups containing from 1 to 3 carbon atoms, and where R_3 , R_4 and R_5 are selected from the group consisting of hydrogen and alkyl group containing from 1 to 3 carbon atoms.

65 3. β -Diethylaminoethyl 2,6-dimethyl benzoate compounds having the fundamental structure:

70 75 4. β -Diethylaminoethyl 2,6-dimethyl benzoate hydrochloride.

9

5. β -Diethylaminoethyl 2,4,6-trimethyl benzoate compounds having the fundamental structure:

6. β -Diethylaminoethyl 2,4,6-trimethyl benzoate hydrochloride.

7. β -Diethylaminoethyl 2,3,5,6-tetramethyl benzoate compounds having the fundamental structure:

8. β -Diethylaminoethyl 2,3,5,6-tetramethyl benzoate hydrochloride.

9. β -Diethylaminoethyl 2,3,4,5,6-pentamethyl benzoate compounds having the fundamental structure:

2,831,016 10

10. β -Diethylaminoethyl 2,3,4,5,6-pentamethyl benzoate hydrochloride.

11. β -Diethylaminoethyl 2,4,6-triethyl benzoate compounds having the fundamental structure:

12. β -Diethylaminoethyl 2,4,6-triethyl benzoate hydrochloride.
